INVENTOR:

FRED . C. OTTO

BY

William E. Baff ATTORNEY.

UNITED STATES PATENT OFFICE.

FRED C. OTTO, OF WORCESTER, MASSACHUSETTS.

RADIATOR.

Application filed April 15, 1921. Serial No. 461,566.

To all whom it may concern:

Be it known that I, FRED C. OTTO, a citizen of the United States, residing at the city of Worcester, in the county of Worcester and State of Massachusetts, have invented new and useful Improvements in Radiators, of which the following is a specification.

This invention relates to improvements in heaters or radiators and has for its object to provide a simple, inexpensive and highly efficient device of this character.

One of the objects of my invention is to provide means for spreading heat rays about a room directly from a stove pipe connected with a regular heater or stove and in such a manner as to permit the hot fumes emanating from the stove and escaping to the chimney to heat a larger surface of the stove pipe than has hitherto been the case.

The principal object of my invention is to provide a radiator which may be coupled securely on a stove pipe or between the sections thereof this type of radiator spreading the heat rays in all directions so as to heat a larger area than is possible without its escape, the escaping products of combustion from the stove effecting the heating operation. I have so shaped, secured, connected and arranged the various parts of my radiator as to make it possible to instantly couple and install any number of similar radiator members or sections in alinement so as to respond in heating surface to the heating requirements of rooms of different size. As a result of the means provided for assembling and coupling such radiator sections it is assured that flame and smoke tight joints are provided between them, each radiator member otherwise being complete in itself.

With the above and other objects in view my invention consists in the combination, arrangement and details of construction disclosed in the drawings and specification and then more particularly pointed out in the appended claims.

In the drawings wherein similar reference characters designate similar parts.

Figure 1 is a side elevation of my invention in use, 50

Figure 2 is a top plan view of a conical section of my heater,

Figure 3 shows respectively side and end views of a bracket,

Figure 4 is a bottom plan view of a deflector secured to a conical section of a heater, 55

Figure 5 shows respectively plan and side views of a coupling member,

Figure 6 is a side elevation of a frusto-conical member, 60

Figure 7 is a side view of said deflector and its support,

Figure 8 is a perspective view of said deflector and support,

Figure 9 is a vertical sectional view thru 65 my invention,

Figure 10 is a side elevation of the parts of my invention,

Figure 11 is a side view of the deflector or spreader proper, and, 70

Figure 12 shows respectively top plan and side views of a coupler member.

Figure 13 is a sectional elevation of a pair of coupling parts,

Figure 14 is a sectional view of one of the 75 coupler sections and

Figure 15 is a sectional view, partly broken away, of another coupling section.

In the drawings which are merely illustrative of my invention my heater or radiator comprising one or more similar units

each of which is composed of the conical sections A and B having their base edges secured together, thus providing a substantially tubular body tapering to narrow in opposite directions from its center.

The upper end of this body 1 has a nipple, the central bulged out portion of this body being designated 2, and where the base edges of

sections A and B abut is designated 4. 90

There is a collar 5 having a flaring flange 6 secured to the frusto-conical section A and to which any section of a stove pipe may be attached.

A hollow deflector consists of the two frusto-conical members 24 and 25 secured together at their base edges and

95

formed with the ports 26. Secured to the conical section 24 of this deflector circumferentially thereof are the angular lugs 23 secured by suitable fasteners thereto and 5 formed upon the hanger straps 21 the upper ends of which straps are inclined to form lugs 22 secured to the inner walls of the upper conical section A. These hanger straps are bridged across the space between 10 the conical sections of my heater and the deflector and serve to hang and support this deflector concentrically within my heater to provide sides inclining in the same general direction but at somewhat different 15 angles with respect to the axis of my heater. This deflector is of a smaller diameter than the heater and is also of a lesser height and its upper and lower ends are spaced respectively from the upper and lower ends of the 20 heater. With this arrangement, the annular passage provided between the deflector and the heater sections is of reduced cross section near the middle of the heater. It will be seen that when my heater is connected 25 as a pipe section to a stove pipe and the hot products of combustion rise to escape thru the chimney the gases will initially expand upwardly and heat the wall of section B of my heater being spread out by the adjacent walls of the deflector and some of the 30 gases will enter this hollow deflector thru ports 26 so as to heat the interior of this deflector. The products of combustion will thereupon be deflected and reduced in volume 35 towards the central portion of the heater so as to impinge all around the section 24 of the deflector and from there expanding and emerging thru the nipple 1 to the chimney and atmosphere.

40 Figure 1 shows a tier or bank of my heaters connected to a stove pipe and in this event it is desirable to bring the heaters as close together as possible so that a suitable coupling to connect them together is desirable. I provide this in the form of two 45 templates or collars 11 and 13, formed conical and secured around the narrow conical ends of the confronting sections A and B of two heaters, these collars being formed 50 with integral pipe portions 10 and 12 having their edges abutting together, and if desired these edges may have a tongue and groove fit as shown in Figure 13 where the annular tongue 15' of one section fits in the 55 corresponding groove 14' formed in the other section. In order to lock these sections together integral lugs 19 are formed around sections 10 and 12 in such a way, as shown in Figure 15, that the lugs of the upper section 60 incline or extend downwardly while those of the lower section incline or extend upwardly both sets of lugs being formed with holes through which bolts project so as to clamp the coupling sections together. It will be 65 seen that when the pipe sections 10 and 12

are fastened together the radiators A, B will be connected in alinement having intervening pipes formed between them, the latter making a good flame and smoke tight joint with said radiator sections. The clamping 70 bolts are designated 18 and have binding nuts 20 thereon. Fasteners 14 secure the collars 13 and 11 to the sections A and B of adjacent heaters passing thru the holes 75 11' formed in these collars.

Numerous modifications may be resorted to in practice without departing in principle from the details of construction herein disclosed.

What I desire to secure and claim by Letters Patent is:—

1. A radiator of the class described, comprising a pair of frusto-conical sections having their base edges secured together, and a deflector supported concentrically within said sections, and spaced therefrom, the said deflector also consisting of frusto-conical sections having their base edges secured together, with the sides of said deflector sections inclined in the same general direction as the sides of said heater sections, but at different angles with respect to the central axis of the radiator, whereby the annular passage between said sections is of reduced width near the middle of the heater. 90

2. In combination with a conical tubular member, a tubular coupling having a flaring flange secured around the lower end thereof, a downwardly inclined integral lug formed upon said coupling and having a hole therein, a tubular coupling having its edge brought together with the edge of the other tubular coupling and also formed with an upwardly extending lug having a hole therein, and means passing thru both holes and clamping both couplings together. 100

3. A coupling for radiator sections consisting of a pair of tubular portions formed with flaring collars for attachment to the radiator sections and having their edges brought together, a series of circumferentially spaced lugs respectively inclining upwardly and downwardly and abutting one against the other, and bolts engaging the pairs of lugs and clamping them together. 110

4. In combination a pair of tubular frusto-conical members having their inner narrow portions confronting, a pair of conical sleeves secured to the last named portions and having pipe sections held in abutting relation, lugs carried by said respective pipe sections in abutting relation, and means for clamping said lugs together. 120

5. Means of connecting radiator sections consisting of a pair of annular members carried by said sections and nested into abutting contact, a circumferential series of integral outwardly projecting lugs formed upon the respective members and adapted to overlap and fasteners tapped into the over- 130

lapping lugs to secure them firmly together.

6. In combination a pair of radiator members having confronting tapering hollow portions, a pair of annular members secured 5 respectively to said hollow portions and joined together to provide a pipe intervening between said hollow portions and communicating with the latter, lugs formed integrally upon said hollow members and 10 projecting across the abutting edges of said

members and means for clamping said lugs together to hold said members against displacement.

In witness whereof I have hereunto set my hand and affixed my seal this 17th day of 15 October, 1919.

FRED C. OTTO. [L.S.]
